W. C. CORTELYOU

MIXER FOR GASEOUS FUEL

Filed April 30, 1921

UNITED STATES PATENT OFFICE.

WILLIAM C. CORTELYOU, OF OBLONG, ILLINOIS.

MIXER FOR GASEOUS FUEL.

Application filed April 30, 1921. Serial No. 465,774.

To all whom it may concern:

Be it known that I, WILLIAM C. CORTELYOU, a citizen of the United States, residing at Oblong, in the county of Crawford and 5 State of Illinois, have invented new and useful Improvements in Mixers for Gaseous Fuel, of which the following is a specification.

This invention has reference to mixers for 10 gaseous fuel and its object is to cause the breaking up of gaseous or spray-like fuel into minute sub-divisions for inter-mixture with air, whereby to facilitate the evaporation of the fuel of initially liquid form so 15 that the inter-mixture of the liquid fuel, (hydro-carbon) with a proportionate quantity of air is particularly intimate.

The invention is designed as an attachment 20 for the intake end of the fuel manifold of a gasoline engine, such for instance as are employed in automobiles, and the attachment is especially adapted for introduction at the discharge end of the carbureter and into the intake neck of the manifold.

25 The invention comprises a cylindrical member, which may be of sheet metal surrounding and holding a sheet of metallic gauze and the cylindrical member is provided with a circular series of vanes on opposite sides of 30 the gauze sheet anchoring the latter in position and providing propeller-like vanes crossing each other on opposite sides of the gauze sheet in such manner that whirling motion is imparted to the flow of fuel toward the engine causing reverse streams of 35 the mixture, whereby these streams are directed first one way and then in the opposite direction, and are forced in exceedingly fine streams toward the engine whereby large 40 quantities of fuel in greatly attenuated form are brought together. This facilitates the inter-mixture, so that there is practically no fuel in liquid form that passes beyond the attachment.

45 In cold weather great trouble has been experienced in starting gasoline engines, due to the condensing of the fuel on the manifold and cylinder walls and trouble is found, even where the engine is warmed up, in such 50 condensation whereby liquid fuel finds its way into the cylinders.

In accordance with the invention, the fuel is so treated that the air and liquid fuel is brought together in such a finely divided 55 state that the fuel is practically all taken up in a gaseous state and intermixed with

the air so intimately as to provide a practically perfect fuel in highly explosive condition, this being due to the fine gauze screen accentuated by the agitation of the air and fuel caused by the reverse beatings imparted thereto by the reversely directed blades or vanes, without, however, such blades or vanes rotating bodily.

The structure forming the subject matter 60 of the invention and reduced to extremely simple form is so constructed that it may be introduced at the junction of the carbureter and intake manifold without any change in the construction of these parts and only necessitating the removal of the screws or bolts holding the two parts together, these screws being usually two in number so that the attachment may be slipped into place and the 65 screws or bolts replaced.

The invention will be best understood 70 from a consideration of the following detailed description, taken in connection with the accompanying drawings forming a part 75 of this specification, with the understanding, however, that the invention is not confined to any strict conformity with the showing 80 of the drawings, but may be changed and modified so long as such changes and modifications mark no material departure from 85 the salient features of the invention as expressed in the appended claims.

In the drawings:—

Figure 1 is an elevation, with some parts 90 in section, of a carbureter and intake manifold of known form, with the attachment inserted.

Figure 2 is an axial section through the attachment.

Figure 3 is a plan view of the gauze element employed.

Figure 4 is a plan view of the element of 95 Figure 2 in display form and omitting the gauze.

Figure 5 is an end view of the attachment 100 in condition to be inserted in the manifold.

Referring to the drawings, there is shown 105 a carbureter 1 in conjunction with an intake manifold 2, neither of which need differ from the named parts, as employed in automobile engines and hence require no special description, the showing of the drawings illustrating a well known form of carbureter and intake manifold in extensive use.

The invention comprises an attachment 3, 110 for insertion in the intake neck of the intake manifold 2 of the engine, so that all the air

and fuel entering the engine is compelled to pass through the attachment for action thereby on the fuel fed to the engine. Such fuel is usually a hydro-carbon fuel, specifically gasoline, although not necessarily limited thereto. Under present day conditions, the specific gravity of commercial gasoline is relatively low and consequently such gasoline volatilizes but sluggishly until the fuel 10 is heated to a relatively high degree, so that frequently gasoline engine conditions preclude the ready evaporation of the fuel and leaves a condition where there is more or less of the gasoline still liquid on reaching the 15 cylinders, to the detriment of running conditions and making starting in cold weather very difficult.

The attachment of the invention comprises an elongated blank formed of an approximately 20 rectangular sheet of metal, bent into a cylinder 4 having slits 5, 6 in succession with these slits dividing the opposite edges of the blank into blades 7 bent, as indicated in dotted lines at 8, toward opposite long 25 edges of the blank at such angles that the blades divert the air streams diagonally toward the axial portion of the attachment. Lodged between the fan blades 7 is a sheet 9 preferably composed of wire gauze of fine 30 mesh and extended transversely of the cylinder 4 to practically intervene throughout the whole area of the interior of the cylinder.

Each blade 7 has one edge 10 formed by 35 the slit 6 so located as to be approximately radial to and substantially in contact with the corresponding face of the gauze 9, thus holding the gauze in place, while the slit 5 is shorter than the slit 6, and is approximately 40 parallel with the axis of the cylinder but the edge of the blade corresponding to the slit 5 is bent out of parallelism so that the whole blade has a skew position imparted to it. This causes the blade to have a propeller effect upon the fuel and air passing through the attachment with the blades on one side opposing those on the other side and displaced by about half the distance between the two blades.

50 The relation of the cuts or slits 5 on one side of the blank is such with relation to the cuts 6 on the other side of the blank as to produce tongues 11 at one end of the attachment and other tongues 12 at the other edge 55 or end of the attachment. The tongues 11 bend outwardly to a small degree so as to catch in the space between the manifold and the adjacent end of the carburetor where they are secured together, thus preventing longitudinal movement of the attachment without taking up sufficient space to interfere with the usual packing gasket employed. The ends 12 are bent inwardly to a small degree so as to facilitate the introduction of 60 the attachment into the mouth of the intake 65

manifold. These ends are somewhat exaggerated in the drawings and may be much less pronounced than the drawings indicate.

What is claimed is:—

1. A mixer attachment for fuel fed to explosion engines, comprising a cylindrical member adapted to be introduced into the intake manifold of the engine, and a gauze division plate intermediate of the ends of the cylindrical member, said cylindrical member having opposed inwardly directed vanes or blades located on opposite faces of the gauze plate and having a lateral inclination about the longitudinal axis of the mixer to impart a twisting motion to the flow of air and fuel passing through the mixer. 70

2. A mixer for fuel fed to explosion engines, comprising a cylinder with two spaced circular series of inwardly tapering vanes 85 fast to the walls of the cylinder and converging toward the central portion of the cylinder on opposite faces of a central plane, each vane meeting the periphery of the cylinder in a line which forms an oblique angle 90 with the elements of the cylinder, and a gauze division plate located in said central plane between the two series of vanes.

3. A mixer for fuel fed to explosion engines, comprising a cylindrical body with 95 slits defining triangular opposed vanes or blades extending inwardly from opposite ends of the cylinder in circular series and having a lateral inclination to impart opposite whirling motion to fluid passing through the cylinder, and an intermediately located gauze partition held in place in the cylinder by the vanes. 100

4. A mixer for air and fuel fed to explosion engines, comprising a cylindrical member adapted to be located in the intake manifold of the engine and provided with two spaced circular series of tapering vanes, and a gauze division plate lodged between the two series of vanes and held thereby, the small ends of the vanes being directed toward and having a lateral inclination about the longitudinal axis of the cylinder, and there overlapping to impart a swirling 110 motion in opposite directions to the mixture traversing the mixer. 115

5. A mixer for breaking up and intermingling fuel and air streams, comprising a substantially cylindrical member adapted to be lodged in the intake manifold of an explosion engine, said mixer having a plurality of circular series of vanes within the cylinder, with the vanes of each series overlapping and having a lateral inclination to impart a swirling motion to the mixture of air and fuel, the vanes of one series being directed oppositely to the vanes of the other series, whereby the mixture is swirled in opposite directions. 120

6. A blank for producing a mixing struc- 125

130

ture for introduction into the manifold of an explosion engine, comprising an elongated sheet of metal with companion pairs of slits entering opposite edges of the sheet, 5 with one slit at approximately right angles to an edge of the sheet and the companion slit at an angle to the same edge and to the first named slit and spaced from the latter, with the slits repeated, to be bent to form 10 two circular series of vanes directed toward the longitudinal axis of the cylinder and tapering toward their free ends to produce vanes for imparting a swirling movement to air and fuel passing through the mixing 15 structure.

7. A blank for forming a mixer to be introduced into a fuel intake passage of an explosion engine, comprising an elongated sheet of metal with series of pairs of slits entering opposite edges of the sheet, the 20 pairs on opposite edges being in staggered relation, the slits forming each pair converging inwardly but not meeting, the line joining the inner ends of the slots being inclined with reference to the longitudinal 25 central line of the sheet.

In testimony that I claim the foregoing as my own, I have hereto affixed my signature.

WILLIAM C. CORTELYOU.
